UNITED STATES PATENT OFFICE.

WILSON L. BURLEY, OF CROCKSVILLE, OHIO.

KILN FOR BURNING EARTHENWARE.

Application filed January 15, 1925. Serial No. 2,671.

My invention relates to improvements in kilns for burning earthenware.

An important object of the invention is to provide a kiln of the above mentioned character in which the preheating, burning, and cooling of the earthenware may be carried out continuously, as the articles are advanced through the kiln.

A further object of the invention is to provide means for regulating the heat within the several zones of the kiln for effecting the proper treatment of the earthenware.

Other objects and advantages of the invention will be apparent during the course of the following description.

In the accompanying drawings forming a part of this specification and in which like numerals are employed to designate like parts throughout the same,

20 Figure 1 is a central vertical longitudinal section through a kiln embodying my invention,

Figure 2 is a horizontal longitudinal section taken on line 2—2 of Figure 1,

25 Figure 3 is a transverse section taken on line 3—3 of Figure 2, and,

Figure 4 is a similar view taken on line 4—4 of Figure 1.

In the drawings wherein for the purpose 30 of illustration is shown a preferred embodiment of my invention, the kiln is shown as including a long kiln casing or shell, 5, formed of suitable refractory material. This kiln casing embodies a longitudinally extending chamber or passage 6, which leads at 35 its lower end into a pit 7, as shown. Mounted upon the bottom of the pit 7 are rails 8 suitably secured thereto, as shown. Air circulating or cooling openings 9 are formed 40 in the side walls of the pit, and lead into the same, above the rails 8.

The side walls of the kiln casing or shell 5 are provided in their lower portions with interior grooves 10, extending longitudinally 45 of the same, throughout their entire length. These grooves are adapted to receive a slab 11, arranged upon a layer of asbestos 12 or other insulating material which is carried by the top 13, of a truck 14. This truck is 50 equipped with wheels 15, traveling upon the rails 8. The longitudinal edges of the slab 11, which is preferably formed of refractory material, project into the grooves 10, as above stated, and I preferably provide strips 55 of asbestos 16, or other insulating material, secured to the bottom walls of these grooves

near and beneath the slab 11. It is thus seen that the slab, grooves and associated elements, constitute cells for preventing the heated gases from passing downwardly into 60 proximity to the truck and parts thereof.

Arranged or formed upon or within the opposite sides of the kiln casing or shell 5 are fire boxes 17. The fuel is fed into these fire boxes through openings 18, in the outer 65 ends thereof. The combustion chambers of these fire boxes discharge directly into the longitudinal chamber or passage 6, as shown at 19. Horizontal longitudinal air supplying flues are formed in the side walls of the 70 kiln casing and also extend through the walls of the fire boxes, as shown. The forward end of these flues are open to the atmosphere while their rear ends are closed. As clearly shown in Figure 4, the horizontal 75 air supply flues 20 lead, at their rear ends, into upstanding flues 21, discharging into a horizontal flue 22, which communicates with a stack 23. This stack is preferably provided in one or both sides with slots or openings 80 24, which may be partly or wholly closed by a brick or bricks, thereby regulating the draft from the stack.

The opposite side walls of the kiln casing are provided with transverse cooling open- 85 ings or flues 25, in communication with the longitudinal flues 20 and the longitudinal chamber 6. These side walls are also provided with transverse draft flues 26, in communication with the rear ends of the flues 90 20 and the chamber 6.

The truck 14 has transverse hollow saggar blocks 27 arranged upon its slab 11, as shown. These saggar blocks are spaced from the side walls of the kiln casing and are of sufficient height to project across the lower portions of the transverse flues 25 and 26, for a considerable distance. The upper portions of these flues extend above these saggar blocks. The earthenware articles 28, 100 to be baked, are arranged upon the saggar blocks.

The intermediate portion of the kiln casing constitutes the baking or heating zone, and is designated generally by A. The end portion B, is the pre-heating zone and the end portion C is the cooling zone.

The truck carrying the earthenware articles to be baked is passed into the pre-heating zone B, and is continuously advanced 110 through the kiln, at a suitable speed. The heated gases or products of combustion act

upon the articles to be baked, as they pass through the pre-heating zone into the heating or baking zone. When the truck passes through the cooling zone, C, the articles of earthenware gradually cool, and this cooling may be had by the heat passing through the transverse cooling flues 25. It is obvious that the products of combustion from the fire boxes 17 discharge into the central portion of the chamber 6, or the baking zone of the kiln, and then pass to the left, into the pre-heating zone. These products of combustion then pass outwardly through the draft flues 26 into the rear ends of the longitudinal flues 20, and then to the stack. By partly or wholly uncovering the opening or slot 24, the draft may be regulated or broken and the heated gases will pass more slowly through the draft flues 26.

20 It is to be understood that the form of my invention herewith shown and described is to be taken as a preferred example of the same, and that various changes in the shape, size, and arrangement of parts may 25 be resorted to without departing from the spirit of my invention or the scope of the subjoined claim.

Having thus described my invention, I claim:

30 In a kiln for burning earthenware, a long kiln casing having side walls forming a longitudinal tunnel, said tunnel having an

intermediate baking zone and pre-heating and cooling zones disposed upon opposite sides of the baking zone, fire boxes arranged upon opposite sides of the tunnel adjacent to the baking zone and discharging directly into the baking zone, said side walls having longitudinal flues formed therein and also in the walls of the fire boxes, said longitudinal flues extending throughout the major portion of the length of the pre-heating zone and the cooling zone, a stack arranged adjacent to the outer end of the pre-heating zone and in communication with the ends of the longitudinal flues, the pre-heating zone having the major portion of its length arranged between the stack and the baking zone, the side walls of the tunnel in the pre-heating zone having transverse flues which lead from the tunnel to the longitudinal flues, the side walls of the tunnel in the cooling zone also having transverse flues leading from the tunnel to the longitudinal flues, said longitudinal flues having their ends adjacent to the cooling zone open to the atmosphere and their ends adjacent to the pre-heating zone closed to the atmosphere, said longitudinal flues being free from direct communication with the fire boxes.

In testimony whereof I affix my signature.

WILSON L. BURLEY.
